REDUCTION OF COPPER CORROSION OF SWEET OILS

Mathew L. Kalinowski and John A. Bolt, Chicago, Ill., assignors to Standard Oil Company, Chicago, Ill., a corporation of Indiana

No Drawing. Application March 12, 1954,
Serial No. 415,947

9 Claims. (Cl. 196—32)

This invention relates to a method for reducing the corrosivity to copper of sweet oils wherein the corrosivity is caused by organic sulfur compounds and/or free-sulfur.

Although the doctor process is probably the most commonly used process for converting the mercaptan in sour petroleum distillates to disulfides, it has some drawbacks. Frequently corrosive sulfur is present in the sweet oil. As the quality requirements of oils has been raised, the presence of corrosive sulfur is more and more deleterious to commercial sale of doctor sweetened petroleum distillates. Although it is possible, by careful control of conditions, to avoid the formation of excessively corrosive oil, upsets in conditions often result in the production of considerable quantities of sweet oil which does not meet copper corrosion specifications. Usually this oil is dumped to a product which has a lower quality demand or is recycled to the sweetening zone. Both of these expedients have an economic penalty.

Oils sweetened by the copper chloride process frequently are corrosive to copper owing to the presence of free-sulfur derived by an oxidation of hydrogen sulfide present in the oil. Hypochlorite sweetened oils are often corrosive to copper.

An object of the invention is a process which includes sweetening and produces a sweet oil of good copper corrosion quality. Another object is the treatment of a doctor sweetened oil of unsatisfactory copper corrosion quality to improve corrosivity as measured by the copper strip test. Other objects will be apparent in the course of the detailed description.

It has been found that a sweet oil which contains corrosive organic-sulfur compounds and/or free-sulfur can be improved with respect to corrosivity to copper by contacting the oil with water soluble alkanolamine in an amount sufficient to form two distinct phases for a time sufficient to remove an appreciable amount of these sulfur bodies, and separating an oil of improved copper corrosivity from the alkanolamine phase. The preferred alkanolamine is triethanolamine and the preferred agent is an aqueous solution of triethanolamine containing between about 2 and 15 volume percent of triethanolamine.

The hydrocarbon oil feed to the corrosion improvement process of this invention may be any liquid hydrocarbon oil which is corrosive to copper owing to the presence of organic-sulfur compounds and/or free-sulfur, and which is essentially free of mercaptans as determined by the doctor test or has a mercaptan number of less than 1. The process is particularly suitable for the treatment of petroleum distillates boiling below about 750° F. Examples of these distillates are industrial naphthas, kerosene, diesel oil, heater oil, gas oil, etc. The process may be used on distillates obtained by the fractional distillation of crude petroleum or on distillates obtained from various conversion processes such as thermal cracking, catalytic cracking, reforming in the presence of hydrogen, etc. Sour petroleum distillates boiling in the heavier-than-gasoline range, i. e., between about 325°

2

and 650° F., e. g., a heater oil boiling between about 330° and 575° F., which have been sweetened by the doctor process, are a particularly suitable feed.

The oil may be corrosive to copper either due to the presence of corrosive organic-sulfur compounds and/or free-sulfur which are not removed in the sweetening procedure, or due to the formation of these corrosive bodies during the sweetening procedure. For example: A copper chloride sweetened oil may be corrosive because free-sulfur developed in storage from the oxidation of H₂S is not removed in the sweetening operation. A hypochlorite sweetened industrial naphtha may be corrosive either because of the presence of free-sulfur developed prior to sweetening or because corrosive bodies are developed in the sweetening procedure. Doctor sweetened oils usually develop corrosiveness in the sweetening.

Since doctor sweetened oils are most prone to being corrosive, this sweetening process is described in some detail. The doctor solution is made up of an aqueous solution of an alkali metal hydroxide and the reaction product of litharge and the alkali metal hydroxide. The amount of free-alkali metal hydroxide present in the doctor solution may be between about 5 and 30 weight percent, usually between about 10 and 15%. The plumbite content is commonly given in terms of the percent of PbO theoretically present. This content for a fresh doctor solution is usually between about 1.5 and 2.5 grams of PbO per 100 cc. of solution.

The temperatures at which the sour oil-doctor-sulfur are contacted in conventional doctor treating are between about 60° and 175° F. The treating temperature may be determined by the flash point of the particular sour oil charged to the process. Thus when operating with naphthas, temperatures on the order of 70° F. may be used; when operating with a kerosene, temperatures between about 90° and 110° F. may be used; and when operating with a high flash point material such as a high boiling furnace oil, temperatures as much as 150° F. or higher may be used. Still another limitation on the contacting temperature may be color formation in the oil, e. g., some kerosenes rapidly develop color bodies when exposed for prolonged times at temperatures above about 120° F.

The amount of doctor solution utilized usually is between about 2 and about 50 volume percent based on sour distillate. More usually, the usage is between about 3 and about 15 volume percent.

Free-sulfur is added to the contacting zone to effect the sweetening. Frequently more than the theoretical quantity of 0.5 mol per each mol of mercaptan sulfur present in the sour oil is needed. The use of the theoretical quantity of free-sulfur does not always produce an oil that is sweet to the doctor test; this is particularly true with heavier-than-gasoline distillates. The amount of excess free-sulfur necessary varies with the sour oil charged and the operating conditions. In general the higher boiling the sour oil, the more excess sulfur that is needed to produce a sweet product.

Frequently, in addition to the use of free-sulfur, free-oxygen is introduced into the sweetening zone. The presence of free-oxygen has a favorable effect on the usage of free-sulfur and also helps to convert some of the PbS formed in the sweetening reaction to the soluble plumbite formed. In general, the amount of free-oxygen added is between about 100 and 300% of that theoretically needed to convert the PbS.

The amines used in the corrosion improvement procedure of this invention are the water-soluble alkanolamines. The term "water soluble" is intended to include those alkanolamines which are sufficiently soluble to have a beneficial effect. Preferably the alkanolamines should be soluble to the extent of at least about 2 volume per-

cent based on doctor solution. The most suitable alkanolamines are those wherein not more than 3 carbon atoms are present in each alkyl group, or conversely, wherein each alkyl group contains from 2 to 3 carbon atoms. Examples of these alkanolamines are mono-, di- and triethanolamine and the propanolamines.

Although the pure or commercial grade alkanolamines are the most effective agents, it is usually more economical to use dilute solutions of these alkanolamines. The dilute solution may consist essentially of the alkanolamine and water, or it may consist essentially of alkali-metal hydroxide, water and alkanolamine, or it may consist essentially of doctor solution (fresh or spent) and alkanolamine. The aqueous solution may contain about 2 volume percent or more. In general, it is preferred to use as the agent an aqueous alkanolamine solution containing between about 2 and 15 volume percent of alkanolamine, preferably triethanolamine.

The amount of alkanolamine agent utilized is at least enough to form a separate phase in the contacting zone. The amount used is dependent in part on the amount of alkanolamine present in the agent. In general, between about 2 and about 100 volume percent of alkanolamine agent is used based on sweet distillate charged to the contacting zone. More usually, the usage is between about 2 and 15 volume percent.

The temperature of contacting is usually at about atmospheric temperature. Higher temperatures may be used although in general temperatures in excess of about 150° F. are not necessary. In general, the temperature of contacting is between about 60° and about 150° F., and preferably about 100° F.

The contacting is carried out for a time sufficient to improve the copper corrosivity of the oil. The minimum time of contacting is related to the temperature of contacting. Roughly, the higher the temperature, the lower the corresponding contacting time. Also, the amount of alkanolamine used has a bearing on the contacting time. In general, the time of contacting should be between about 15 minutes and 90 minutes. When operating at about 100° F., a suitable time is between about 30 and 45 minutes.

The results obtainable with the process are illustrated by the following working examples. It is to be understood that these examples are illustrative only and do not limit the sphere of usefulness of the process.

EXAMPLE A

In this example, the sweet oil was produced by doctor sweetening a heavy naphtha fraction which had the following characteristics:

API gravity	46°
RVP	0.5
Sulfur, weight percent	0.1
ASTM, °F.:	
Initial	330
10%	343
50%	370
90%	428
Max.	460

This sour oil was contacted at 100° F. with 4 volume percent of fresh doctor solution containing 1.8 grams of PbO per 100 cc. of solution. The free-sulfur usage was 50% in excess of the theoretical requirement. The sour oil, doctor solution and free-sulfur were agitated until the oil was sweet. The sweet oil was decanted from the lower layer of doctor solution and water washed to remove entrained doctor solution. The sweet oil was freed of water by passage through a filter paper coalescer. This oil was sweet to the doctor test.

The corrosiveness of the sweet oil was determined by the Bolt copper strip technique which is described in the Oil and Gas Journal of August 9, 1947. In this technique, a copper strip is immersed for three hours in the

oil which is maintained at a temperature of 212° F. In this technique a perfect strip is assigned the number "0." The higher the number assigned to the strip, the more corrosive the oil. In run 1 the sweet oil as prepared above had a copper strip of 7.

The effect on copper strip of contacting the sweet oil with alkanolamine was studied using triethanolamine. The sweet oil was contacted with 10 volume percent of agent for 45 minutes at a temperature within the range, 90°-100° F. The sweet treated oil was decanted from the lower triethanolamine agent phase and water washed to remove agent. For purposes of comparison, two runs were carried out using aqueous sodium hydroxide containing 10 weight percent of caustic. One run was carried out contacting the sweet oil with the aqueous sodium hydroxide alone. Another run was carried out using aqueous sodium hydroxide containing 5 volume percent of triethanolamine.

The results of these tests are set out in Table I.

Table I

Run No.	Agent	Copper Strip Number
1.	none	7
2.	100% T.E.A.	4
3.	5% T.E.A.; 95% water	5
4.	10% aqueous NaOH	7
5.	5% T.E.A.; 95% (10% aqueous NaOH)	5

These runs show that contacting the sweet oil with aqueous NaOH alone had no effect on the copper corrosivity of the oil. Further, they show that either water or aqueous caustic can be used in connection with the alkanolamine to obtain the desired (Runs 3 and 5) improvement in corrosivity. Runs 2 and 3 show that the use of commercial grade anhydrous triethanolamine was more effective than 5% aqueous triethanolamine when the time and temperature conditions of contacting were the same but the lower concentrations are more economical.

EXAMPLE B

In this example, the sour oil was a kerosene having the following characteristics:

API gravity	43.4°
Sulfur, weight percent	0.09
ASTM distillation, °F.:	
Initial	344
10%	378
50%	426
90%	473
Max.	513

This sour kerosene was sweetened under conditions very similar to that of Example A except that in this case the free-sulfur usage to obtain a sweet product was 226% in excess of theory.

The sweet kerosene was contacted with the same agents as used in the runs of Example A. In this example the sweet kerosene was contacted with the agent for 30 minutes at a temperature range between 100° and 110° F. The results of these tests are set out in Table II.

Table II

Run No.	Agent	Copper Strip Number
6.	none	9
7.	100% T.E.A.	6
8.	5% T.E.A.; 95% water	7½
9.	10% aqueous NaOH	9
10.	5% T.E.A.; 95% (10% aqueous NaOH)	7

These tests show that the process is about equally effective in improving the corrosivity of kerosene as for a

heavy naphtha, i. e., a reduction in copper strip number of about 3 units.

It is to be understood that the contacting of the sweet oil and the alkanolamine agent may be any of the various methods known to the art. For example, the contacting may be carried out batch-wise in a single operation followed by gravity settling and decantation from a single vessel. Or, the contacting may be carried out in a continuous manner using a tower type of contactor. The agitation in the contacting zone may be imparted by air blowing, orifice mixers, or by mechanical agitation.

Thus having described the invention what is claimed is:

1. A process for improving the copper corrosivity of a doctor sweetened oil which comprises (1) intimately contacting a sour petroleum distillate boiling in the heavier-than-gasoline range with doctor solution and with free-sulfur in an amount sufficient to sweeten said distillate, at a temperature between about 60° and 175° F., for a time sufficient to substantially sweeten said distillate, (2) separating said substantially sweet distillate from doctor solution, (3) contacting said substantially sweet distillate with water soluble alkanolamine agent in an amount sufficient to form separate distillate and alkanolamine phases, at a temperature between about 60° and about 150° F., for a time between about 15 minutes and 90 minutes and (4) separating a sweet distillate of improved copper corrosivity from an alkanolamine agent phase.

2. The process of claim 1 wherein said agent is triethanolamine.

3. The process of claim 1 wherein said alkanolamine is diethanolamine.

5 4. The process of claim 1 wherein said alkanolamine is monoethanolamine.

5 5. The process of claim 1 wherein said alkanolamine is propanolamine.

10 6. The process of claim 1 wherein said distillate is a kerosene.

7. The process of claim 1 wherein said distillate is a heater oil.

15 8. The process of claim 1 wherein said alkanolamine agent usage is between about 2 and about 100 volume percent, based on distillate.

9. The process of claim 1 wherein said alkanolamine agent consists of between about 2 and 15 volume percent of triethanolamine and the remainder essentially water.
